UNITED STATES PATENT OFFICE.

ARTHUR N. CALKINS, OF FRANKLIN, NEW JERSEY, ASSIGNOR TO AMERICAN MATCH MACHINE COMPANY, OF NEW YORK, N. Y.

MATCH-SPLINT CARRIER.

SPECIFICATION forming part of Letters Patent No. 681,872, dated September 3, 1901.

Application filed December 8, 1900. Serial No. 39,212. (No model.)

To all whom it may concern:

Be it known that I, ARTHUR N. CALKINS, a citizen of the United States of America, and a resident of Franklin, county of Essex, State 5 of New Jersey, have invented certain new and useful Improvements in Match-Splint Carriers, of which the following is a specification, reference being had to the accompanying drawings, forming a part thereof.

10 My invention relates to improvements in match-splint carriers and particularly to the means for locking the splints in said carriers.

My invention consists in improved means for locking the splints in a carrier and in 15 means for rotating a match-splint about its longitudinal axis to a predetermined position when it has been presented to the carrier in an undesired position and in locking it in the position to which it has been so rotated.

20 In carrying out my invention I employ a locking bar or plate having an orifice therethrough of sufficient size to freely receive and to permit the free passage therethrough of a match-splint, the said orifices having a restricted extension which upon the relative 25 movement of the match-splint with the bar or plate transversely of the match-splint grips the said splint and locks it in position. I preferably provide these said bars or plates

30 pairs and mount them upon a frame, so that the said bars or plates have a movement relatively to each other and to the frame, the frame and plates each having coincident orifices of such size to permit the passage freely 35 therethrough of a match-splint, the orifices in the plates or bars having oppositely-arranged restricted extensions which will clamp the sides of the match-splint upon the said relative movement. I preferably cut away

40 one of the sides of each of the said orifice extensions at about the point at which it unites with the main portion of its orifice to a greater extent than the other. The projecting shoulder thus formed causes the rotation of a match- 45 splint about its longitudinal axis to a predetermined position when such match-splint has been presented out of such position.

The objects of my invention are to simplify the construction and the operation of a 50 match-splint carrier, to lock the splints se-

curely in the said carrier, but in locking them to reduce to a minimum the liability of breakage, and to straighten or aline to a predetermined position a match-splint during or before the operation of locking.

55

I will now proceed to describe a match-splint carrier embodying my invention and will then point out the novel features in claims.

60 In the drawings, Figure 1 is a face view of a match-splint carrier embodying my invention with the locking plates or bars in position ready to receive the splints. Fig. 2 is a face view of a match-splint carrier embodying my invention with the locking bars or 65 plates in the positions which they assume in locking the match-splint. Fig. 3 is a face view of a portion of the frame having mounted thereon a pair of locking-plates, the locking-plates being in similar relative positions 70 to those shown in Fig. 1. Fig. 4 represents a transverse section upon the plane of the line 4 4 of Fig. 3. Figs. 5, 6, and 7 are detail views, on an enlarged scale, of portions of the locking-plates and showing more clearly the 75 form or shape of the locking-orifices therein and the manner in which they operate upon the match-splint.

80 The splint-carrier frame or support in the present example of my invention is shown as a rectangular block and designated by the reference character 8. This block may conveniently be made of wood for lightness and cheapness, but may be made of any other desired material. It has a plurality of orifices 9, 85 which are here shown as arranged in a series of transverse rows. As shown herein, there are twenty of these orifices to a row and forty-eight rows to a frame. Each orifice is arranged to receive a single match-splint, and 90 thus one frame is arranged to carry nine hundred and sixty splints. The orifices 9 are of sufficient size to permit a match-splint to pass freely through the frame.

95 The frame 8 is provided with a series of locking plates or bars arranged in pairs, each pair being movable with respect to each other and to the frame, but independent of any of the other bars or plates. I will, for purposes of this specification, describe one pair of these 100

plates or bars, and it will be understood that such description will apply equally well to all the others.

The locking plates or bars, which are respectively designated by the reference characters 10 and 11, are superposed upon each other and together secured to the frame by means of screws 12, which pass through slotted openings 13 in the said bars or plates. Such connection permits a small relative longitudinal movement of the plates with respect to each other and to the frame.

The locking-plates 10 and 11 are each provided with a plurality of match-splint receiving and locking orifices 14. These orifices are of sufficient size to permit the free passage therethrough of a match-splint. In Figs. 5, 6, and 7 this relation of size is fairly illustrated, the portion designated by the reference character 15 being intended to represent a match-splint in transverse section. The locking plates or bars are so arranged with respect to each other and to the frame that in one of their positions the orifices in the said plates or bars and the orifices in the frame are substantially coincident. They are in such relative positions in Figs. 1, 3, 4, and 5 of the drawings, and when in such positions match-splints will pass freely therethrough, as illustrated in Fig. 5. For clearness and simplicity of illustration I have shown but a few of the orifices 14 in the locking plates or bars in Figs. 1 and 2, the first pair of locking plates or bars in each view being the only ones which are shown with their full complement of orifices. It will be understood, of course, that the other locking plates or bars illustrated in these figures are similar to those of the first series.

The orifices in the locking plates or bars 10 and 11 have each a restricted extension 16, (see more particularly Figs. 5, 6, and 7,) the said extension being arranged substantially in the line of movement of the said plates.

The width of the restricted extension 16 in its smallest part is somewhat less than the width of the match-splint to be carried. If the locking-plates be moved longitudinally of each other, they will finally assume a position such as is shown in Figs. 2 and 7 of the drawings. A match-splint presented within the orifices 14, as in Fig. 5, will upon such movement be gripped at the sides thereof parallel with the line of movement of the plates or bars, as clearly shown in Fig. 7.

It will be noticed by an examination of such figure, however, that the match-splint is not necessarily gripped upon those of its sides which are transverse to the said line of movement of the said locking plates or bars, and by reason of such provision the danger of severing or breaking the match-splint due to a slight overthrow of the locking plates or bars is obviated. The grip upon the sides of

the match-splint is of such a quality that after the splints have been locked in position the

locking plates or bars are themselves held against accidental displacement, due to the frictional contact upon the sides of the match-splints, without any independent means being necessary for such a purpose.

The plates or bars are shown as turned up at their ends, as at 17, and these turned-up ends form convenient surfaces against which cams or other devices may be applied in order to obtain the desired relative movement thereof. The means, however, for causing this relative movement of the plates with respect to each other forms no part of this present invention, and hence no detail description of same is given herein.

In order to take care of match-splints which are not correctly presented to the locking-plates and to correctly align and position same, I have provided means whereby a match-splint may be rotated longitudinally of its axis. In this manner the match-splints may be rotated to the desired and predetermined position and afterward locked in the position to which they have been so rotated. For this purpose I have cut away one side of the extensions of the orifices at about the point at which they unite with the main portion of their orifices to a greater extent than the other. The effect of this is to leave shoulders or projecting portions 18 upon the opposite sides thereof. When the locking plates or bars 10 and 11 are moved relatively to each other in the direction shown by the arrows in Figs. 5, 6, and 7 from the position shown in Fig. 5 to the position shown in Fig. 7, the shoulders 18 will engage with a match-splint which has been presented otherwise than with its smallest diameter in a line parallel with the line of movement of the locking plates or bars and will rotate same about its longitudinal axis until it is brought into a position with its sides parallel with the said line of movement, as shown in Fig. 7. Fig. 6 shows the locking plates or bars in an intermediate position, with the shoulders 18 engaging with the splint and rotating it, as just described.

Many modifications of the precise form and construction of my invention herein shown and described are possible, as is and will be obvious to those skilled in the art to which this invention appertains. I do not, therefore, desire to limit myself to the exact details herein.

What I claim is—

1. A carrier for match-splints having means therein for rotating a match-splint about its longitudinal axis to a predetermined position, and for locking it in the position to which it has been so rotated.

2. A plate or bar, for a match-splint carrier, having an orifice therethrough of sufficient size to permit the free passage therethrough of a match-splint, the said orifice having a restricted lateral extension adapted to clamp the sides of a match-splint upon a

- relative movement of the match-splint with the bar or plate, transversely of the match-splint.
3. In a match-splint carrier, the combination of two locking-plates movable with respect to each other, each plate having an orifice for receiving a match-splint, the said orifices having convergent sides which run in opposite directions in the said plates.
4. In a match-splint carrier, the combination of two plates or bars relatively movable with respect to each other, each plate or bar having an orifice therethrough of sufficient size to permit the free passage therethrough of a match-splint, and the said orifices having each a restricted extension, oppositely arranged, for clamping the match-splint upon the relative movement of the plates or bars, with respect to each other.
5. In a match-splint carrier, the combination of two plates or bars relatively movable with respect to each other, each plate or bar having an orifice therethrough of sufficient size to permit the free passage therethrough of a match-splint, and the said orifices having each a restricted extension, oppositely arranged, for clamping the match-splint upon the relative movement of the plates or bars, with respect to each other, such clamping action taking place at the sides of the match-splint parallel with the line of movement of the plates or bars.
6. In a match-splint carrier, the combination of two plates or bars relatively movable with respect to each other, each plate or bar having an orifice therethrough of sufficient size to permit the free passage therethrough of a match-splint, and the said orifices having each a restricted extension, oppositely arranged, for clamping the match-splint upon the relative movement of the plates or bars, with respect to each other, such clamping action taking place only at the sides of the match-splint parallel with the line of movement of the plates or bars.
7. In a match-splint carrier, the combination with a frame having an orifice therethrough of sufficient size to permit the free passage therethrough of a match-splint, of a locking plate or bar, relatively movable with respect to said frame, transversely of the said orifice, and also having an orifice therethrough of sufficient size to permit the free passage therethrough of a match-splint, said last-named orifice having a restricted extension, adapted to clamp the sides of the match-splint upon the said relative movement of the said plate or bar and frame.
8. In a match-splint carrier, the combination with a frame having an orifice therethrough of sufficient size to permit the free passage therethrough of a match-splint, of two plates or bars mounted upon said frame and relatively movable with respect to each other and to the frame, each plate or bar having an orifice therethrough adapted to register with each other and with the orifice in the

frame, said orifices in the plates or bars also being of sufficient size to permit the passage therethrough of a match-splint, and each 70 having a restricted extension, oppositely arranged, for clamping the match-splint, upon the said relative movement of the bars or plates.

9. In a match-splint carrier, the combination with a frame having an orifice therethrough of sufficient size to permit the free passage therethrough of a match-splint, of two superposed plates or bars mounted upon said frame, means whereby the plates or bars 80 may be moved in opposite directions relatively longitudinally of each other and in opposite directions relatively to the frame, said plates or bars having orifices therethrough of such size and shape as to permit the free 85 passage therethrough of a match-splint before said movement and to clamp the match upon said movement.

10. In a match-splint carrier, the combination of two locking-plates movable with respect to each other, each plate having an orifice for receiving a match-splint, the said orifices having convergent sides which run in opposite directions in the said plates, and the convergent sides in a said orifice being 95 unsymmetrical, as and for the purpose set forth.

11. In a match-splint carrier, the combination of two plates or bars relatively movable with respect to each other, each plate or bar 100 having an orifice therethrough of sufficient size to permit the free passage therethrough of a match-splint, and the said orifices having each an oppositely-arranged restricted extension, one side of each said extension being 105 cut away, at about the point at which it unites with the main portion of its orifice, to a greater extent than the other.

12. In a match-splint carrier, the combination of two locking plates or bars movable 110 with respect to each other, and having rigid locking - surfaces, each of the said plates adapted in its movement to clamp both the two sides of a match-splint parallel with the line of the said movement. 115

13. In a match-splint carrier, the combination of two locking plates or bars movable with respect to each other, and having rigid locking - surfaces, each of the said plates adapted in its movement to clamp both and 120 only, the two sides of a match-splint parallel with the line of the said movement.

14. A locking plate or bar, for a match-splint carrier, having an orifice therethrough of sufficient size to permit the free passage 125 therethrough of the match-splint, the said orifice having a restricted lateral extension, of substantially the form and shape shown in the drawings.

ARTHUR N. CALKINS.
